WINDOW REGULATOR

Filed April 5, 1926

UNITED STATES PATENT OFFICE

STANLEY W. NICHOLSON, OF TOLEDO, OHIO, ASSIGNOR TO THE DURA COMPANY, OF
TOLEDO, OHIO, A CORPORATION OF OHIO

WINDOW REGULATOR

Application filed April 5, 1926. Serial No. 99,926.

The invention relates to window regulators and refers more particularly to that type of window regulator having a pivotal lifter arm for actuating a window. Some of the objects of the invention are the manufacture of a lifter arm which may be formed of comparatively light gage sheet metal and which is so constructed that it effectively resists both bending and twisting stresses and the forming of a gear segment rigidly secured to the lifter arm for angularly moving the same by means of an arcuate rack and the locating of the ends of this rack relative to the lifter arm by means of the reinforcing means for the lifter arm.

Other objects of the invention reside in the novel features of construction and combinations and arrangements of parts as more fully hereinafter set forth.

In the drawings:—

Figure 1 is an interior side elevation of a portion of a vehicle door having applied thereto a window regulator embodying my invention;

Figures 2 and 3 are cross sections on the lines 2—2 and 3—3, respectively, of Figure 1.

The window regulator embodying my invention is shown in the present instance upon the vehicle door 1 having the opening 2 in its upper portion and the chamber 3 in its lower portion for receiving the window 4 when lowered from a position closing the opening.

For the purpose of reducing the cost of manufacture of the window regulator, the mounting plate 5, the pivotal lifter arm 6 and the gear segment 7 are formed of stampings. The mounting plate, as shown, has the body 8 which is laterally spaced from the sheet steel lock board 9 and extends substantially parallel thereto. At the upper end of this body there are the legs 10 which terminate in the tongues 11 having the laterally spaced inner and outer portions 12 and 13 for engaging the outer and inner sides respectively of the lock board at different elevations, the tongues extending through the apertures 14 in the lock board. 15 is a spacer located centrally of the lower end of the body 8 and rigidly secured thereto and 16 is a

screw extending through the lock board and threaded into the spacer for securing the mounting plate to the lock board and placing the mounting plate under stress.

The lifter arm 6 is pivotally mounted near its inner end upon the mounting plate and is suitably connected at its outer end to the window. For reinforcing the lifter arm against both bending and twisting stresses so that this lifter arm may be made of relatively light gage sheet metal, I have provided the ribs 17 and 18 which extend longitudinally of the lifter arm and project laterally therefrom toward the mounting plate. The rib 17 is located substantially centrally of the lifter arm and is in the nature of a bead while the rib 18 is located at the lower edge of the lifter arm and is in the nature of a flange. For spacing the main portion of the lifter arm from the body of the mounting plate, I have provided the depressed bosses 19 and 20, respectively, upon the lifter arm and the mounting plate and extending toward and bearing against each other. These bosses are centrally apertured to receive the pivot which is in the nature of a pin 21 having the shouldered portion 22 located in the recess formed by the boss 20 and bearing against the inner side of this boss. This pin also has a shouldered portion located in the recess formed by the boss 19 and bearing against the outer side of this boss to thereby secure the lifter arm to the mounting plate. To lock the pin from rotation relative to the lifter arm, I form the recesses 23 in the boss 19 and communicating with the central opening therein and form projections upon the outer end of the pin for engaging these recesses. Both the shouldered portion and the projections upon the outer end of the pin are formed by swaging the pin at peripherally spaced points 24. With this arrangement, the pin rotates in the mounting plate and is fixedly secured to the lifter arm. 25 is the counterbalancing spring having one end secured to the mounting plate and the other end secured to the pin as by extending through a transverse slot 26 in its inner end.

The gear segment 7 is in the nature of an arcuate rack which may be formed from a

flat sheet metal strip by curving the strip and then forming teeth in its outer edge by a suitable coining operation. The ends of this arcuate rack are rigidly secured to the lifter arm by suitable means such as spot welding, these ends being so located upon the lifter arm that the teeth of the rack are concentric with the axis of the pivot for the lifter arm. To locate the ends of the rack and at the same time assist in rigidly securing the same to the lifter arm, I make use of the ribs 17 and 18 of the lifter arm. As shown, the rib 18 abuts against one end of the rack while the rib 17 abuts against the other end. In addition to locating the rack, the ribs also assist in holding the teeth of the rack against the teeth of the pinion 27, which is driven from the crank 28.

From the above description, it will be seen that I have provided a construction of window regulator which may be cheaply manufactured and in which the mounting plate, lifter arm and gear segment are formed of stampings of relatively light gage sheet steel. It will also be seen that the means for reinforcing the lifter arm against both bending and twisting stresses also serves to locate the gear segment and more specifically the arcuate rack, which is connected to the lifter arm and additionally serves to hold the teeth of this gear segment or arcuate rack from movement away from the teeth of the driving pinion. In addition to these features, it will be seen that I have provided a novel means for pivotally connecting the lifter arm to the mounting plate and rigidly securing the pivot to one of the members.

What I claim as my invention is:

1. In a window regulator, the combination with a gear segment, of a pivotal lifter arm rigidly secured to said segment and means for reinforcing said arm against bending and twisting stresses and for locating said segment.
2. In a window regulator, the combination with a sheet metal arcuate rack, of a pivotal sheet metal lifter arm rigidly secured to the ends of said rack and means for reinforcing said arm against bending and twisting stresses, including a centrally located longitudinal rib and a second longitudinal rib at an edge of the arm, each of said ribs locating an end of said rack.
3. In a window regulator, the combination with an arcuate rack, of a pivotal lifter arm rigidly secured to the ends of said rack and means upon said arm for reinforcing the same against bending and twisting stresses, said means comprising ribs extending laterally from said arm in the same direction, one of said ribs being centrally located and locating an end of said rack relative to said arm and the other of said ribs being located at the lower edge of said arm and locating the opposite end of said rack.

4. In a widow regulator, the combination with a sheet metal mounting plate, of a sheet metal lifter arm pivotally mounted upon said plate, a sheet metal arcuate rack rigidly secured at its ends to said lifter arm, bosses upon said lifter arm and mounting plate and extending toward and bearing against each other, a pivot extending through said bosses and rigidly secured to one and rotatably secured to the other, and ribs upon said lifter arm and locating the ends of said rack.

5. In a window regulator, the combination with a sheet metal mounting plate, of a pivotal sheet metal lifter arm, apertured bosses upon said mounting plate and lifter arm extending toward and bearing against each other, one of said bosses having recesses communicating with its aperture and a pin extending through the apertures of said bosses for pivotally connecting said lifter arm to said mounting plate, said pin having portions extending into the recesses for non-rotatably securing said pin to said member having the recesses.

In testimony whereof I affix my signature.

STANLEY W. NICHOLSON.
